UNITED STATES PATENT OFFICE.

RICHARD RICHARDSON, OF BEDFORD, NOVA SCOTIA, CANADA.

HOOP-FORMING MACHINE.

1,369,982.

Specification of Letters Patent.

Patented Mar. 1, 1921.

Application filed April 21, 1919. Serial No. 291,670.

To all whom it may concern:

Be it known that I, RICHARD RICHARDSON, a subject of the King of Great Britain, and resident of the town of Bedford, in the 5 Province of Nova Scotia, Dominion of Canada, have invented certain new and useful Improvements in Hoop-Forming Machines, of which the following is a specification.

This invention relates to improvements in 10 hoop-forming machines, and the objects of the invention are to facilitate bending wooden or metallic hoops to the desired curvature and with a minimum of time and labor, to provide means for the ready adjustment of the machine, to properly guide the strips from which the hoops are formed into a machine and discharged therefrom when formed into hoops, and generally to adapt the various parts to better perform 15 the functions required of them.

With the above and other objects in view the invention consists essentially of the improved construction hereinafter described and set forth in the following specification 20 and accompanying drawings:

In the drawings:

Figure 1 is a side elevation of the improved machine, the frame and metallic band being broken away.

Fig. 2 is a plan view of the improved machine showing the frame and metallic band broken away.

Fig. 3 is an end view of the improved machine.

Fig. 4 is a perspective view of one of the guide members and ejectors.

Like characters of reference refer to like parts in the several figures.

Referring to the drawings, A represents 40 the improved hoop forming machine comprising a frame 10 operatively supported adjacent to the ends by legs 11 and 12.

The frame 10 is provided adjacent to one end with a pair of guides 13 adapted to slidably support a bearing block 14, which is 45 capable of being moved longitudinally of the frame 10 by means of a spindle 15 threaded through the end of the frame, the spindle being provided on the outer end with a hand wheel 16 by means of which the spindle is manually rotated.

The inner end of the spindle 15 carries

a washer or plate 17 and between this washer or plate and the end of the bearing block 14 a spring 18 is located, which will 55 give a certain amount of resiliency to the bearing block, and assist in tensioning in a manner to be made clear hereafter.

On the block 14 a shaft 19 is journaled, and on this shaft a corrugated flanged bending wheel 20 is rigidly mounted, and above the pulley a pressure roller 21 is rotatably mounted in the bifurcated end of a bracket 22 which is slidably mounted in the guides 23. The corrugations are not sharp and the 65 object is to make indentures at short intervals, which will make the hoops bend more easily and satisfactorily without breakage, and an important result of this crimping of the hoops is that they are much more pliable 70 and can be worked very much more easily. The pressure roller 21 keeps the band against the strips of wood and thereby keeps the strips of wood against the corrugations, so that uniform indentures are made over 75 the whole length of the hoop.

The bracket 22 is connected to the lower end of the threaded spindle 24 which passes through a threaded portion of the guide frame 23, and the spindle is formed with an 80 enlarged head 25 having hand grips 26 thereon by means of which the spindle is manually rotated.

On the manual rotation of the spindle the bracket 22 will be moved vertically, and it 85 should be clearly understood that the lower end of the spindle makes rotatable engagement with the bracket, but while the spindle is rotated, the bracket is not rotatable.

On adjusting the spindle 24 the pressure 90 roller 21 may be caused to coact with the periphery of the corrugated flanged bending wheel 20 with the desired positive pressure.

Adjacent to the pulley 22 a guide bracket 95 27 is secured to the upper member of the frame 10 and depending from this guide bracket is an ejector 28, the lower end of which is arranged in alinement with the corrugated flanged bending wheel 20.

On the opposite end of the frame a shaft 29 is journaled, and this shaft carries a corrugated flanged bending wheel 30 similar to the corrugated flanged bending wheel 20,

and around the corrugated flanged bending wheel 30 and corrugated flanged bending wheel 20 an endless metallic band 31 extends. Coacting with the corrugated flanged bending wheel 30 is a pressure roller 32 similar to the pressure roller 21. The pressure roller 32 is carried by a bracket 33 slidably mounted in the guides 34, the bracket being connected with the upper end of the 10 spindle 35 which makes threaded engagement with the guide frame 34 and the lower end of the spindle is formed with an enlarged end 37 having hand grips thereon.

As the spindle 35 is adjusted the bracket 15 33 is moved in a vertical direction, so that the pressure roller 32 will coact with the corrugated bending wheel 30, and the desired pressure will thus be obtained.

On that end of the shaft 29 remote from 20 the corrugated flanged bending wheel 30 a pinion wheel 39 is mounted, which meshes with a pinion 40 carried by the shaft 41 rotatably mounted in a bearing superimposed on the frame 10. The shaft 41 is 25 also provided with a belt pulley 42 by means of which rotary motion is transmitted to the corrugated flanged bending wheel 30 and coacting band 31.

On the lower member of the frame 10 30 a guide 43 is rigidly mounted and from this guide an upwardly extending ejector 47 extends which is arranged in alinement with the corrugated flanged bending wheel 30.

When this machine is in operation rotary 35 motion is transmitted, to the belt pulley 42 and thence through the pinions 40 and 39, to the corrugated flanged bending wheel 30, which in turn drives the band 31 and corrugated flanged bending wheel 20.

40 As the band is driven the strips of material pass around the periphery of the bending wheels 30 and 20 and between the same and the band 31, and the desired curvature is given to the strips of material, which on 45 becoming disengaged from the corrugated bending wheels 30 and 20 will be engaged by the ejectors and delivered to the side of the machine.

The desired pressure of the band 31 on 50 the corrugated wheels 30 and 20 can be attained by regulating the pressure of the rollers 21 and 32 on the band 31. If the band requires tensioning this may be accomplished by rotating the spindle 15 so 55 moving the block 14 longitudinally of the frame and exerting the desired pull on the band 31.

The strips from which the hoops are to be formed are hand fed through the guides 60 27 and 43 to the corrugated bending wheels 20 and 30 respectively, and as strips are being carried around the said pulleys by the band 31 indentures are made on the inner face of the strips which render the

said strips much more easily worked after 65 being ejected from the machine.

After the strips pass around the pulleys they engage the curvilinear face of the ejectors 47 or 28 depending at which end of the machine the strips have been fed 70 into the machine.

Each strip is then thrown sidewise out of the machine. The pliability of the strips after passing through the machine render them capable of being bent into closed formation to make a complete hoop. When it is found necessary to tension the metallic band 31, then the hand wheel 16 is rotated thereby moving the spindle 15 longitudinally and the washer or plate 17 coacting with the 80 spring 18 moves the block 14 longitudinally, so that the corrugated bending wheels will thus be spaced farther apart and give the proper tension to the band. The spring will provide a certain amount of cushioning effect and permit of a certain yield of the block and thus there will be no hard jarring actions exerting on the bearing wheels when the hooks are being passed around the bending wheels beneath the metallic band. 90

As many changes could be made in the above construction, and many apparently widely different embodiments of my invention, within the scope of the claims, constructed without departing from the spirit 95 or scope thereof, it is intended that all matter contained in the accompanying specification and drawings, shall be interpreted as illustrative and not in a limiting sense.

What I claim as my invention is: 100

1. A hoop former of the class described, comprising a frame, a corrugated flanged bending wheel on one end of the frame, a corrugated flanged bending wheel on the other end of the frame, a band engaging 105 the corrugated flanged bending wheels, pressure rollers coacting with each of the corrugated wheels and pressing the band into contact therewith, a guide member on the frame adjacent to each corrugated wheel, and an 110 ejector extending from each guide and arranged in alinement with the adjacent corrugated wheels.

2. A hoop former comprising a frame, a corrugated flanged bending wheel on each 115 end of the frame, an endless band engaging the wheels, pressure rollers coacting with each wheel and adapted to press the band against the wheels, slidable brackets carrying the pressure rollers, threaded spindles 120 for moving the brackets, a guide member adjacent to each wheel, and an ejector carried by each guide member and arranged in alinement with the adjacent wheel.

3. A hoop former, comprising a frame, 125 a corrugated flanged bending wheel, rotatably mounted at one end of the frame, a block slidably mounted on the frame, a cor-

rugated flanged bending wheel rotatably mounted on the block, an adjustable spindle, a washer carried by the spindle coacting with the block, a spring on the spindle between the end of the block and the washer, 5 a band engaging the wheels, and pressure rollers coacting with the band and wheels.

In witness whereof I have hereunto set my hand in the presence of two witnesses.

RICHARD RICHARDSON.
